DESIGN FOR A SPRAY GUN

Sigmund E. Edelstone, Chicago, and Albert L. Jenks, Dixon, Ill., assignors to Dupli-Color Products Company, Chicago, Ill., a corporation of Illinois

Application December 18, 1947, Serial No. 143,202

Term of patent 7 years

(Cl. D62—2)

To all whom it may concern:

Be it known that we, Sigmund E. Edelstone and Albert L. Jenks, citizens of the United States, residing, respectively, at Chicago, in the county of Cook and State of Illinois, and Dixon, county of Lee, and State of Illinois, have invented a new, original, and ornamental Design for a Spray Gun, of which the following is a specification, reference being had to the accompanying drawing, forming a part thereof, in which

Figure 1 is a perspective view of a spray gun embodying our new design, a container with which the gun may be used being indicated in dotted lines;

Fig. 2 is a side elevational view thereof;

Fig. 3 is an end view of the spray gun taken from the handle end thereof, the container indication being omitted; and

Fig. 4 is a bottom plan view of Fig. 3.

The characteristic features of our design reside in the portions shown in full lines.

We claim:

The ornamental design for a spray gun, substantially as shown and described.

SIGMUND E. EDELSTONE.

ALBERT L. JENKS.
